UNITED STATES PATENT OFFICE.

EVA TYNER, OF CANON CITY, COLORADO.

DESIGN FOR CANDY.

Application filed August 31, 1922. Serial No. 3,607. Term of patent 3½ years.

To all whom it may concern:

Be it known that I, EVA TYNER, a citizen of the United States of America, residing at Canon City, in the county of Fremont and State of Colorado, have invented a new, original, and ornamental Design for a Candy, of which the following is a specification, reference being had to the accompanying drawing, forming a part hereof.

The drawing is a side elevation of a candy showing my new design.

The design is embodied more particularly in candy consisting of a cream center and a shape-retaining crust or shell.

I claim:

The ornamental design for a candy, as shown.

MRS. EVA TYNER. [I. S.]
